UNITED STATES PATENT OFFICE

141,178

DESIGN FOR A BROOCH OR SIMILAR ARTICLE

James A. Thunder, Chicago, Ill.

Application January 13, 1945, Serial No. 117,418

Term of patent 7 years

(Cl. D45—19)

To all whom it may concern:

Be it known that I, James A. Thunder, a citizen of the United States and a resident of the city of Chicago, in the county of Cook and State of Illinois, have invented a new, original, and ornamental Design for a Brooch or similar article, of which the following is a specification, reference being had to the accompanying drawing, forming a part thereof.

On the drawing:

Figure 1 is a plan view of the brooch, or similar article, showing my new design;

I claim:

The ornamental design for a brooch or similar article, as shown.

JAMES A. THUNDER.
